UNITED STATES PATENT OFFICE.

ARTHUR C. FERGUSON, OF BROOKLYN, NEW YORK.

DIRECT-KEY-LEVER TYPE-WRITER.

SPECIFICATION forming part of Letters Patent No. 717,374, dated December 30, 1902.

Application filed February 21, 1902. Serial No. 95,087. (No model.)

To all whom it may concern:

Be it known that I, ARTHUR C. FERGUSON, a citizen of the United States, residing at Brooklyn, in the county of Kings, State of New York, have invented certain new and useful Improvements in Direct-Key-Lever Type-Writers, of which the following is a specification, reference being had therein to the accompanying drawings.

10 This invention relates to a direct-key-lever type-writer, and particularly to a structure in which the type-bar support is mounted above the carriage.

The invention has for an object to provide 15 an improved construction of type-bar support having alining and locking recesses for the type-bars when the same are placed into printing position.

A further object of the invention is to provide 20 a construction whereby the diametrical center of the type-bar support is above the platen carried by the paper-carriage.

Another object of the invention is to provide 25 a key-lever bearing directly upon the type-bar and provided with means for operating an escapement mechanism and a ribbon-feed mechanism as the bars are depressed for the printing operation.

A further object is to provide an improved 30 construction of type-bar support which is pivotally mounted at one side and capable of reciprocation at an angle to its pivot transversely of the carriage beneath the same.

Other and further objects and advantages 35 of the invention will be hereinafter set forth and the novel features thereof defined by the appended claims.

In the drawings, Figure 1 is a plan of the 40 invention. Fig. 2 is a vertical section on the line 2 2 of Fig. 1. Fig. 3 is a detail perspective of the type-bar support and its mounting. Fig. 4 is a detail end view of the shifting means for said support, and Fig. 5 is a detail plan of the escapement mechanism.

45 Like letters of reference refer to like parts throughout the several figures of the drawings.

The letter A refers to the base, which may 50 be of any desired construction or configuration and provided at the front with opposite standards A', upon which the type-bar support B is mounted. At the rear of the base a

carriage C is mounted to reciprocate thereon and is provided with a platen C' and guard C² at the rear. This carriage is provided with a 55 rack-bar C³, adapted to engage suitable escapement mechanism D, provided with dogs of ordinary construction, which mechanism is pivotally mounted upon the base at D' and provided with a lever-arm D², extending to 60 the front of the machine beyond the type-bar support B. The platen is adapted to be rotated by a handle C⁴ at one end and the feed-pawl C⁵ at the opposite end engaging a ratchet C⁶. The carriage is actuated by means of 65 the winding-drum C⁷, of ordinary construction, having the spring C⁸ connected thereto and a cord C⁹, extending from the periphery of the drum to the carriage, as shown by dotted lines in Fig. 1.

70 The type-bar support is provided at opposite sides with supporting-arms B', one of which is pivotally mounted upon a pin A² by means of the lug B², and at the opposite side a lug B³ forms a hook extending over the pin 75 A² from the standard A'. A suitable catch B⁴ may be used with this hook to prevent a vertical movement of the support. This support is provided with a series of recesses or grooves B⁵ upon its upper surface, extending 80 radially from the center of the support, and upon the periphery lugs B⁶ are provided, between which the type-bars E are mounted, by means of a continuous pivoting rod E', adapted to fit grooves B⁷, formed upon the 85 periphery of the lugs B⁶. In the illustration of the invention type E² have been omitted from most of the bars and keys from the levers in order not to obscure the other parts.

Beneath the grooves or recesses B⁵ cases or 90 shells E³ are radially disposed opposite openings B⁸ in the support, and connected to the inner end of these cases are coiled springs E⁴, having their outer end pivotally secured at E⁵ to the lower end of the type-bar E, thus 95 providing means for restoring the bars to an elevated position. The support B is adapted to be shifted laterally of the carriage and at a right angle to its pivot B² by means of a key-lever F, having at its lower end F' a 100 universal joint connecting with a link F², pivotally secured at its opposite end to the support B, as shown in Fig. 4. Each of the type E² is supplied with two characters—for

instance, capitals and small characters—so that the lateral shifting will permit the use of another character from that used when the support is in its normal position.

- 5 For the purpose of depressing the type-bars E a series of key-levers G are provided, one in alignment with each bar and each provided with a key G'. These levers are pivoted at their outer ends to a fixed ring or support G², 10 carried from the type-support B by means of an arm G³, (see Fig. 2,) and the upward movement of the lever G is limited by means of an annular stop G⁴, supported from the support G² by means of lugs G⁵. The inner ends 15 of the levers G are bifurcated, as shown at G⁶, and fit over the type-bars E. The escapement mechanism D is connected at its forward end D² with a universal bail or loop H, extending beneath the key-levers, and pivoted 20 at the rear by means of the arms H' upon the support G². The depression of one of the key-levers carries downward the loop H and the outer end of the lever D² to operate the escapement mechanism for feeding the carriage. This loop is provided at the front 25 with a key H² for depressing the loop to space when the key-levers are not used. The ribbon mechanism comprises a spool I, carried by hangers I', extending downward from the 30 rear of the support G², and a spool I², supported by hangers I², depending from the front of the support G², as shown in Fig. 2. The oscillating loop H of the escapement mechanism is provided with a depending arm I⁴, passing 35 through a guide-lug I⁵ from the hangers I³ and provided with a spring-pressed pawl I⁶, adapted to engage a ratchet I⁷, carried by the journal of the spool I², so that in the ascending movement of the loop H the spool is rotated to 40 feed the ribbon after the type have left the printing position upon the platen. A ribbon I⁸ passes from one spool to the other and is supported in any desired manner—for instance, by means of a rod I⁹—so as to carry it above 45 the platen and beneath the type-bar support.
- From the foregoing description it will be seen that a depression of the key-levers G will carry downward the type-bar and type, placing the spring E³ under tension and also 50 depressing the loop H to operate the escapement mechanism. When the pressure is removed from the key G', the spring E⁴ restores the type-bars and key-levers to their initial position in contact with the guard G⁴, while 55 the loop H is raised by the flat restoring-spring D³, extending from the base to the escapement mechanism, and the ribbon-spool I² thereby rotated. It will be seen that the type-bar support provides recesses for locking 60 each of the type-bars in positive alignment when depressed for printing, and this support is so mounted that all of the parts carried thereby may be lifted from the platen by means of the pivot B² whenever desired and 65 shifted laterally of the platen when it is desired to use other characters. It will also be observed that this support is mounted so that

its diametric center, or the center of the type to be used, is directly above the platen C' of the carriage. This construction of type-writer provides a simple and economically-constructed device in which the type-bars are positively depressed by the key-levers into their printing position, and the depressing thereof actuates the escapement and ribbon-feed mechanisms, whereby an accurate alignment is secured and a rapid operation of the keys permitted, thus effecting a machine which can be very cheaply constructed and perform the most efficient character of work. 70 75 80

It will be obvious that changes may be made in the details of construction and configuration of the several parts without departing from the spirit of the invention as defined by the claims. 85

Having described my invention and set forth its merits, what I claim, and desire to secure by Letters Patent, is—

1. In a type-writer, a type-bar support provided with a recess upon its upper face, a type-bar pivoted adjacent to said recess and adapted to enter the same when in printing alignment, and means carried by said support below the type-bar pivot for restoring the bars when depressed; substantially as specified. 90 95

2. In a type-writer, a type-bar support provided with a series of recesses for receiving and alining the type-bars disposed radially to a central point and a series of openings through the support beneath and in line with said recesses; substantially as specified. 100

3. In a type-writer, a paper-carriage, a type-bar support, a type-bar mounted therein, a key-lever pivoted at its lower end at one side of said bar and bearing at its upper free end upon the outer face of said type-bar to operate the same by a direct downward movement, and means for restoring said type-bar and lever when depressed; substantially as specified. 105 110

4. In a type-writer, a carriage provided with a platen, an annular type-bar support, mounted above said platen, a series of pivoted type-bars carried by said support and adapted to contact with said platen, and a series of circumferentially-arranged key-levers pivoted at their lower ends below the plane of the type-bar pivots and slidingly bearing at their upper free ends upon said bars; substantially as specified. 115 120

5. In a type-writer, a carriage provided with a platen, an annular type-bar support mounted above said platen and diagonally to the horizontal plane thereof, a series of type-bars carried by said support and adapted to contact with said platen, a series of circumferentially-arranged key-levers pivoted at one end to said support and bearing at their opposite free ends upon said type-bars, and an escapement mechanism operated by the depression of said key-levers; substantially as specified. 125 130

6. In a type-writer, a type-bar support having a series of radially-disposed recesses upon

its upper face and a series of openings beneath the recesses, a series of type-bars disposed upon the outer periphery of said support, a pivoting rod passing through each of said bars, and springs passing through said openings connected to said bars; substantially as specified.

7. In a type-writer, an annular type-bar support, type-bars carried thereby, arms at opposite sides of said support one of which is pivotally mounted and the other adapted to removably engage a bearing, and a standard provided with a pivot for said support; substantially as specified.

15 8. In a type-writer, an annular type-bar support, type-bars carried thereby, arms at opposite sides of said support one of which is pivotally mounted and the other adapted to removably engage a bearing, a standard provided 20 with a pivot for said support, and means for shifting said support longitudinally of its pivot; substantially as specified.

9. In a type-writer, an annular type-bar support, type-bars carried thereby, arms at opposite sides of said support one of which is pivotally mounted, a standard provided with 25 a pivot for said support, a key-lever mounted upon said standard, and a connection from said lever to said pivoting arm for shifting the same longitudinally of its pivot; substantially as specified.

10. In a type-writer, an annular type-bar support provided upon its upper face with a series of radially-disposed recesses, lugs upon 35 its outer face, type-bars pivoted between said lugs, a series of radially-disposed springs connected to said type-bars, and casings for supporting the inner ends of said springs; substantially as specified.

40 11. In a type-writer, a base, a carriage provided with a platen, an annular type-bar support located above said platen, type-bars pivoted at their lower ends to said support, and key-levers pivoted at their lower ends at one 45 side of said bars and bearing thereon with their upper ends above the pivots of the bars; substantially as specified.

12. In a type-writer, a base, a carriage provided with a platen, an annular type-bar support located with its diametric center above said platen, type-bars carried by said support, an annular supporting-ring supported from said type-bar support concentric thereto, key-levers pivoted at their lower ends to 55 said ring and bearing at their upper free ends upon said type-bars, and keys carried by said levers to exert a direct downward movement thereon; substantially as specified.

13. In a type-writer, a base, a carriage provided with a platen, an annular type-bar support located with its diametric center above said platen, type-bars carried by said support, an annular supporting-ring supported from said type-bar support, key-levers pivoted at one end to said ring and bearing at 60 their opposite end upon said type-bars, keys

carried by said levers, an escapement mechanism coöperating with said carriage; and a pivoted loop beneath said key-levers for operating said escapement mechanism; substantially as specified.

14. In a type-writer, a base, a carriage provided with a platen, an annular type-bar support located with its diametric center above said platen, type-bars carried by said support, an annular supporting-ring supported from said type-bar support, key-levers pivoted at one end to said ring and bearing at their opposite end upon said type-bars, keys carried by said levers, an escapement mechanism coöperating with said carriage, a pivoted loop beneath said key-levers for operating said escapement mechanism, ribbon mechanism depending from said supporting-ring, and means carried by said loop for intermittently feeding said ribbon mechanism; substantially as specified.

15. In a type-writer, a base, a carriage provided with a platen, an annular type-bar support located with its diametric center above said platen, type-bars carried by said support, an annular supporting-ring supported from said type-bar support, key-levers pivoted at one end to said ring and bearing at their opposite ends upon said type-bars, keys carried by said levers, an escapement mechanism coöperating with said carriage, a pivoted loop beneath said key-levers for operating said escapement mechanism, ribbon mechanism depending from said supporting-ring, means carried by said loop for intermittently feeding said ribbon mechanism, a standard for supporting said type-bar support, and a key for shifting the same upon said standard; substantially as specified.

16. In a type-writer, a base, a carriage provided with a platen, an annular type-bar support located with its diametric center above said platen, type-bars carried by said support, an annular supporting-ring supported from said type-bar support, key-levers pivoted at one end to said ring and bearing at their opposite ends upon said type-bars, keys carried by said levers, an escapement mechanism coöperating with said carriage, a pivoted loop beneath said key-levers for operating said escapement mechanism, a ribbon mechanism depending from said supporting-ring, means carried by said loop for intermittently feeding said ribbon mechanism, a standard for supporting said type-bar support, a key for shifting the same upon said standard, a stop for limiting the upward movement of said key-levers, and a series of radially-disposed restoring-springs connected to the lower ends of said type-bars; substantially as specified.

17. In a type-writer, a type-bar support, a type-bar pivoted thereon, a key-lever pivotally mounted at its lower end at one side of and bearing upon said type-bar at its upper free end, a key upon said lever for causing

downward movement thereof, and means for restoring said type-bar and key-lever; substantially as specified.

18. In a type-writer, a type-bar support, a type-bar pivoted thereon, a key-lever pivotally mounted at its lower end at one side of and bearing upon said type-bar at its upper free end, a key upon said lever for causing downward movement thereof, means for restoring said type-bar and lever; escapement means, a carriage coöperating therewith, and means lying beneath said key-lever for operating said escapement; substantially as specified.

19. In a type-writer, an annular type-bar support, type-bars mounted thereon, an annular supporting-ring beyond said bar-support, a carriage beneath said bar-support, and escapement mechanism having an extended lever-arm, key-levers mounted upon said ring and bearing upon said type-bars, a pivoted loop beneath said key-levers engag-

ing said lever-arm, ribbon-spools depending from said supporting-ring, an arm depending from said loop, a ratchet-wheel carried by 25 a one spool of the ribbon mechanism, and a spring-pressed pawl carried by the depending arm from said loop; substantially as specified.

20. In a type-writer, a type-bar support, a type-bar pivoted thereon between its ends, a restoring-spring carried by said support and connected to the lower end of, said type-bar, a key-lever having a bifurcated end in contact with said type-bar, and a pivot-support 35 for said lever extended beyond the bar-support; substantially as specified.

In testimony whereof I affix my signature in presence of two witnesses.

ARTHUR C. FERGUSON.
